FLUORESCENT LIGHTING FIXTURE

Max M. Thomsen, Moundsville, W. Va., assignor to Sylvania Electric Products Inc., Salem, Mass., a corporation of Massachusetts

Application July 13, 1956, Serial No. 42,237

Term of patent 14 years

(Cl. D48—19)

Fig. 1

Fig. 2

Fig. 3

Fig. 4

Figure 1 is a bottom perspective view of a fluorescent lighting fixture showing my new design;

Figure 2 is a side elevational view thereof;

Figure 3 is a bottom plan view thereof; and

Figure 4 is an end view thereof.

I claim:

The ornamental design for a fluorescent lighting fixture, as shown.
